[57] ABSTRACT

A dynamic shrimp grader and grading method of universal application to all types of shrimp which in a first

embodiment (FIGS. 1–6) utilizes a series of sequential, slightly inclined trays, each having a number of parallel V-shaped channels with grading slots at their end. The trays are mounted on an upper frame which is driven by an eccentric drive upwardly and simultaneously forwardly with respect to the grader's basic support structure, imparting a dynamic action, the upper frame and basic support structure being connected together by a number of angularly disposed, flexible reinforced fiberglass strip springs. Shrimp enter at the top of the grader moving down the channels under the dynamic action of the moving trays and are graded by their width, the smaller falling through the slots in the upper trays, the slot width and length becoming larger from each upper tray to the succeeding lower tray. The shrimp are aligned generally vertically by the sides of the channel and have a tendency to flatten out under the dynamic action of the trays as they progress down the channel (FIG. 8A–8C). The V-shaped channels are formed by means of joining together an alternating series of flat strips (FIG. 5) or alternatively by appropriately bending a single strip (FIGS. 5A). A second embodiment (FIG. 7) utilizes a single flat tray with a staggered series of progressively larger, grading holes therein in place of the trays with the V-shaped channels of the first embodiment.

DYNAMIC SHRIMP GRADER AND GRADING METHOD

BACKGROUND OF THE INVENTION

The present invention relates to a grading machine and method thereof for grading and separating all types of shrimp including headless or heads-on shrimp, pre-cooked or not, and peeled or not. The present invention more particularly relates to a dynamic shrimp grading machine, and a method of grading, which includes an inclined tray or trays which are moved upwardly and forwardly, driving the shrimp down the trays and grading them according to size by means of either terminal slots or circular holes, which get progressively larger as the shrimp move down the machine.

Heretofore, there has been a long standing desire and need in the commercial shrimp processing industry for a shrimp grader which has universal application to all types and conditions of shrimp, is highly accurate in its grading, is relatively compact, achieves a large number of size gradings within a short distance, causes no damage to the shrimp which are particularly delicate after peeling, and has no real cleaning or jamming problems. All prior shrimp graders suffered from the lack of one or more of the foregoing desired characteristics, while the present invention offers the first real achievement of these goals.

A typical example of a prior art shrimp grader which has been used by the commercial shrimp processing industry with less than completely satisfactory results is shown in the U.S. Pat. to Demarest et al. (No. 2,964,181, issued Dec. 13, 1960) which uses a series of Archimedes-type screws positioned above an inclined pan, the distance between each screw and the pan serving to grade the shrimp. The Demarest machine however suffers from problems of inaccuracy caused by different size shrimp becoming intermixed during grading, with smaller shrimp riding "piggy-back" on the larger shrimp being moved by the screws, causing them to be graded out through the wrong slot. Additionally, the Demarest machine in practice is applicable only to peeled, headless shrimp.

The present invention overcomes all of these prior art deficiencies by providing a dynamic system which positively moves the shrimp without any damage down the grading structure and, by its action on the shrimp, causes the shrimp to more properly align itself for grading, and yet achieves this action in a structure which is highly compact, allowing a relatively large number of grading sizes within a relatively short span. This dynamic action is achieved by mounting the grading trays on a series of reinforced fiberglass-strip springs angularly mounted to the basic support structure of the grader, the upper tray structure then being eccentrically driven upwardly and forwardly by means of an eccentric motor drive. Universality of application is achieved by utilizing in the grading structure easily interchangeable grading trays, one type being a series of juxtaposed trays having a parallel set of V-shaped channels terminating in grading slots or, alternately, a single, continuous tray having a series of circular grading apertures therein.

Additional objects and advantages of the present invention will be apparent from an understanding of the details of the structure and method of use of the present invention, which will be fully disclosed with reference to the description of the preferred embodiments

below read in conjunction with the attached drawings which will now be briefly described.

BRIEF DESCRIPTION OF THE DRAWINGS

FIGS. 1 through 4 are perspective, top, side, and end views, respectively, of a first embodiment of the dynamic shrimp grader of the present invention, FIG. 1 showing headless, unpeeled shrimp being processed; while

FIGS. 5 and 6 are end cross-sectional and top views, respectively, of the V-shaped channel trays used in FIGS. 1-4, the former figure showing some of the channels of a tray while the latter figure shows only a single channel.

FIG. 5A, similar in perspective to FIG. 5, shows an alternate embodiment of the construction of the V-shaped channels.

FIG. 7 is a perspective view of an alternate embodiment of the grading tray structure which can be utilized on the grading machine of FIGS. 1-4 in place of the V-shaped grading trays of the first embodiment.

FIGS. 8A through 8C are side views, partially cut away, of a headless, unpeeled shrimp in one of the V-shaped channels, showing the shrimp's tendency to become extended out in more of a straight line rather than maintaining its normal full curvature, due to the dynamic action of the tray, as the shrimp progresses down the channel.

DESCRIPTION OF THE PREFERRED EMBODIMENTS

As illustrated in FIGS. 1-4, the dynamic shrimp grading machine of the present invention includes an upper size grading structure which is mounted on upper frame member 2 which is flexibly and movably mounted by means of angularly disposed, reinforced fiberglass springs 5 with respect to the lower frame member 3 which in turn is fixedly supported by basic, inverted U-shaped support legs 4 with respect to the ground. The upper frame member 2 and hence the tray grading structure mounted thereon is initially driven upwardly and forwardly in continuing cycles by means of a reciprocating eccentric drive.

As seen particularly in FIG. 3, the reciprocating eccentric drive includes an electric motor 6 which by means of belt 7 drives an eccentric motion producing element 8. The eccentric 8 through hanger arm 9 and connectorhead 10 drives with a general reciprocating action the upper portion of fiberglass spring support 5, which in turn imparts the dynamic action to the upper frame member 2 utilized in the present invention.

Each fiberglass spring support 5 includes a strip of strong but flexible fiberglass material connected to the upper and lower frame members 2, 3 by means of angle blocks 16. Because of the angular disposition, i.e., the angular off-set from the vertical, of the support strips 5, the upper frame structure 2 moves upwardly and forwardly before returning to its original position for another cycle.

Although the structure particularly illustrated and described herein with respect to the reciprocating eccentric drive and the mounting structure between the frame member 2, 3 produces the best embodiment presently known, the structure lends itself easily to much variation in the motion by merely, for example, varying such factors as the angular disposition and length of the strip 5, the stroke of the eccentric 8, and

the speed of the motor 6. The resultant motion however must be sufficient to align and give a forward impetus to the shrimp, and yet not be such as to cause damage to the delicate shrimp meats.

A series of juxtaposed, downwardly inclined, grading trays 1a-1d are fixedly mounted on the upper frame member 2 by means of a series of vertical channel iron supports 15.

Each tray 1 (a-d) includes a set of parallel, V-shaped channels 13 each ending in an identically dimensioned grading slot 12, the slot structure being shown in close-up detail in FIG. 6. The initial portions 14 of the channels 13 are solid in order to provide a preliminary space upon which the shrimp can fall without hitting a grading slot. Were the shrimp to fall directly unto a grading slot, larger shrimp would have a tendency to become wedged in the slot.

The length as well as the width of the slots 12 is particularly important for the best grading operation of the machine, and the two are interdependent. As a general rule, all shrimp of a particular thickness have substantially the same effective length. Thus all shrimp having a thickness of the order of seven-eighths of an inch will have generally a length of 6 inches. For maximum effectiveness the length of the grading slot 12 should be substantially equal to the effective length of the shrimp whose thickness is identical to the width of that particular slot. Were it to be much greater, some shrimp would have a tendency to jam in the slot even though it was of a size normally to go pass that slot; and were it substantially shorter, some of the shrimp which should have fallen through the slot, will pass it.

Beneath the grading slots 12 are suspended downwardly inclined, collection and conveying pans 11 which are mounted on the lower support structure 3 of the machine. The laterally disposed pans 11 serve to separately collect and convey the graded shrimp out of the grading machine for subsequent processing such as packaging. Each pan 11 can be mounted in like fashion on fiberglass strip spring and be dynamically moved with respect to the upper frame structure to enhance its conveying capability by causing the shrimp to be driven down its surface.

As many grading trays 1 (a-d) with differing size grading slots 12 can be provided as desired in view of the ultimate number of separation or grades needed. A final collecting pan extending longitudinally out of the machine is provided at the end of the final tray 1d in place of the end member 14 to collect all those shrimp which are still too large to pass through the slot 12d. The machine will thus produce a total number of size grade levels equal to the number of grading trays 1 (a-d) plus one.

The trays 1 (a-d) are uniform in length and are designed to be easily removed from the vertical supports 15 so that the sizing or grading dimensions produced by the machine can be readily, easily and quickly changed as desired.

As an alternate embodiment, rather than the series of trays 1 (a-d) with the terminal slots 12 as described above, a single tray having a series of staggered, progressively larger, circular apertures 112 with a single channel 113 is also provided (note FIG. 7). Such a tray 101 has been found to be particularly effective in grading peeled cooked shrimp and is designed to be mounted on the same vertical supports 15 which supported the trays 1 (a-d). The vertical supports 15 have

an additional set of bolt holes to mate with the corresponding holes in the sides of the tray 101 for easy interchangeability of the tray structures. Such easy substitution of grading tray structures greatly enhances the flexibility of the grading machine of the present invention and allows its universality of application to all types and conditions of shrimp.

As best illustrated in FIG. 5, each tray 1 (a-d) can be made up of a series of, for example, stainless steel or aluminum angle strips 17, connected together by means of 90° angle members 18 which also serve to add strength and rigidity to the tray structure. Alternately, as illustrated in FIG. 5A, each V-shaped channel can be made of a single strip bent into the more up-right configuration illustrated. As shown in FIG. 5A, the up-right configuration comprises a first, lower, central section 50 emanating out from the apex 51 and a second, upper section 52 also emanating out but at less an angle than said first section. The angle 52 between the walls of said two sections thus are less than 180°.

The sloping sides of the V-shaped channels 13 serve to centrally and vertically align and position the shrimp, regardless of size, for highly accurate grading. Although such has not been found to be necessary, a friction-reducing and easily cleanable surfacing substance such as "Teflon" can be coated on the working surface of the strips 17.

The eccentrically driven, upper portion of the grading machine provides a very important dynamic action which produces very advantageous and useful effects on the shrimp as they progress down the machine, greatly enhancing its size - grading accuracy.

The dynamic action of the machine causes the shrimp to have a powered effect or dynamic action as it moves down the grading channel 13 (113). This dynamic action causes the shrimp to become separated from each other and, in the V-shaped embodiment, insures the near up-right or vertical alignment of the shrimp due to the support and guidance produced by the sides of the V-shaped channel. The machine thus inherently and accurately aligns the shrimp parallel to the length of the grading slot insuring accurate grading.

Moreover, in the case of headless shrimp, the dynamic action of the machine causes the shrimp to unbend to some degree as it moves down the grading channel. This latter action is illustrated in FIGS. 8A through 8C, although somewhat exaggerated in the figures for illustrative purposes. The more straightly aligned the shrimp become, the more accurate will be the grading because of the improved face-to-face contact the shrimp then has when it meets the grading aperture 12 (112).

The face-to-face contact is further improved by the dynamic aspects of the machine because the shrimp is being driven down against the trays 1 (a-d) (101) during the initial impulse of the eccentric drive when the tray is beginning to rise. Hence, upon contact, opposing but controlled and limited forces are created at the time the grading slot and the shrimp meet, further enhancing the grading accuracy of the machine.

Suitable dimensions for the grading machine described above and illustrated are as follows:

Typical Dimensions

Element	Dimension
Overall Width of Machine	48"
Overall Length of Machine	14'
Length of Trays 1a-1d	25"

Typical Widths of Slots 12a-12d	5/16"; 3/8"; 7/16"; 9/16"
The Respective Lengths of Slots 12a-12d	4"; 4 1/2"; 5"; 5 1/2"
Angle of Inclination of Trays 1a-1d	5°
Angle of V-Shaped Channels 13	90°
Length of Strips 5	10"
Width of Strips 5	2"
Thickness of Strips 5	1/4"
Angle of Inclination of Strips 5 (From horizontal)	60°
Stroke of Eccentric 8	5/8"
Speed of Rotation of Eccentric 8	500 RPM
Length of Tray 101	14"
Typical Diameters of Apertures 112	7/16"; 1/2"; 9/16"; 5/8"; 3/4", etc.

Method of Operation

The method of operation of the foregoing described machine is as follows.

Processed shrimp, usually coming from a wash tank prior to grading, is conveyed to the top of the shrimp grader and the shrimp to be graded are fed by conveyor down onto the initial solid portion 14 of tray 1a, with the shrimp being divided as equally as possible between the various channels 13. Under the upward, forward and downward motion of the trays, the shrimp begin to progress down the tray 1a in separate, single file fashion, and those shrimp which are small enough to fit through the slots 12a fall down into the collecting and conveying pan 11a. The larger shrimp continue to move down the channels 13 of tray 1a until they fall down onto the initial portion 14 of juxtaposed tray 1b and, in like fashion, move down trays 1b, 1c and 1d until all the shrimp have been graded through the slots 12 which are analogous to their width.

The separated and graded shrimp are then conveyed out of the machine by means of pans 11 for further processing, including usually a final inspection and ultimately packaging.

The method of operation when using the alternate tray 101 of FIG. 7 is the same with the exception that of course there is no dropping from one set of trays to another, there being only one continuous, downwardly inclined tray 101. When using the tray 101, the shrimp are graded according to their diameter when laid on their sides. Because tray 101 is used with cooked, peeled shrimp, the straightening action of the shrimp as discussed above with respect to FIGS. 8A-8C is not effective because the cooked peeled shrimp curl basically into a circle and lie on sides on the tray 101. This is, of course, as desired when grading cooked, peeled shrimp.

Because many varying and different embodiments may be made within the scope of the inventive concept herein taught and disclosed, and because many modifications may be made in the embodiments herein detailed in accordance with the descriptive requirements of the law, it is to be understood that the details herein are generally speaking to be interpreted as illustrative only, and not in a limiting sense.

What is claimed as invention is:

1. A dynamic shrimp grading machine for grading shrimp according to their size comprising:
an upper frame portion;
a basic frame support structure;
mounting means for mounting said upper frame portion to said basic frame support structure in such a manner as to allow said upper frame portion to be moved at least forwardly and backwardly along the longitudinal axis of the machine;
drive means for moving said upper portion with respect to said basic frame support structure at least

forwardly along the longitudinal axis of the machine and then cyclically and continuously repeating itself; and

tray grading means mounted on said upper frame portion for grading and separating the shrimp according to size, said tray grading means including a series of size-grading apertures therein which progressively get larger as said tray grading means is progressed, said tray grading means including a series of adjacent, juxtaposed inclined trays, each comprising a series of elongated channels, each of said channels having a substantial, extended, initial portion which is solid and an end portion which terminates in a grading slot of uniform width, said solid portion serving as a non-grading portion upon which the shrimp can fall or be moved and said slot serving as said size-grading aperture; whereby shrimp placed on the top of said grading tray means are dynamically moved down said grading tray means and are separated and graded according to size by the smaller ones falling through the earlier encountered grading apertures and the larger shrimp falling through the larger grading apertures as the shrimp progress down said grading tray means.

2. The dynamic shrimp grading machine of claim 1 wherein said mounting means further allows an initially upward motion along with the forward motion to cause the shrimp to have a "hippity-hop" action as they progress through the machine.

3. The dynamic shrimp grading machine of claim 1 wherein said tray grading means is one continuous, inclined pan having a series of circular apertures therein of progressively larger diameter throughout substantially all of its length.

4. The dynamic shrimp grading machine of claim 1 wherein said mounting means comprise a series of angularly disposed, elastic strips, the termination portions of which are attached to said basic frame support structure and said upper frame portion.

5. The dynamic shrimp grading machine of claim 1 wherein said drive means includes the following:

source of rotary motive power;
eccentric drive means for changing the circular rotary motion to reciprocating eccentric motion;
drive means for feeding the rotary motion of said source of motive power to said eccentric drive means; and
connector rod drive means for transmitting the reciprocating eccentric motion produced by said eccentric drive means to said upper frame portion.

6. The dynamic shrimp grading machine of claim 1 wherein said end portion of each of said trays is physically removed from said initial portion of the succeeding tray, each of said trays being higher than and overlapping the succeeding one.

7. The dynamic shrimp grading machine of claim 6 wherein each of said channels has a V-shaped cross-section, the walls of said channel freely supporting the shrimp in an upright position for enhanced grading accuracy.

8. The dynamic shrimp grading machine of claim 7 wherein said walls have two sections, an upper and a lower, the wall segments of said lower section converging to the apex of the V-shaped cross-section and emanating out therefrom to join with the wall segments of said upper section, the wall segments of said upper sec-

tion likewise emanating out but at a less angle than said first section, the angle between the wall segments of said upper and lower sections having less than a 180° angle between them.

9. The method of grading shrimp according to their size comprising the following steps:

- a. providing a grading structure comprising an upper frame portion;
- a basic frame support structure;
- mounting means for mounting said upper frame portion to said basic frame support structure in such a manner as to allow said upper frame portion to be moved at least forwardly and backwardly along the longitudinal axis of the machine;
- drive means for moving said upper portion with respect to said basic frame support structure at least forwardly along the longitudinal axis of the machine and then cyclically and continuously repeating itself;
- tray grading means mounted on said upper frame portion for grading and separating the shrimp according to size, said tray grading means including a series of size-grading apertures therein which progressively get larger as said tray grading means is progressed; whereby shrimp placed on the top of said grading tray means are dynamically moved down said grading tray means and are separated and graded according to size by the smaller ones falling through the earlier encountered grading apertures and the larger shrimp falling through the larger grading apertures as the shrimp progress down said grading tray means;
- b. dumping shrimp unto the top of said tray grading means;
- c. moving said upper frame portion initially in an upwardly direction to a limited extent and then forwardly to thereby positively and dynamically drive the shrimp down the grading tray means;
- d. continuously repeating the movement of step c until the shrimp have either fully progressed the grading tray means or have fallen through said grading apertures; and
- e. collecting the shrimp from under said grading apertures and conveying them out of the machine for further processing.

10. The method of claim 9 wherein in moving said upper frame portion, the shrimp are driven so that they follow a "hippy-hop" action as they progress down said grading tray means.

11. The method of claim 10 wherein, in driving said upper frame portion upwardly and forwardly, the shrimp are driven so that they have a tendency to unbend to some degree away from their normally curled disposition.

12. A dynamic shrimp grading machine for grading shrimp according to their size comprising:

- an upper frame portion;
- a basic frame support structure;
- mounting means for mounting said upper frame to

said basic frame support structure in such a manner as to allow said upper frame portion to be moved at least forwardly and backwardly;

drive means for moving said upper portion with respect to said basic frame support structure at least forwardly along the longitudinal axis of the machine and then cyclically and continuously repeating itself;

tray grading means mounting on said upper frame for grading and separating the shrimp according to size, said tray grading means including a series of size-grading apertures therein which progressively get larger as said tray grading means is progressed; whereby shrimp placed on top of said tray grading means are dynamically driven down said tray grading means and are separated and graded according to size by the smaller ones falling through the earlier encountered grading apertures and the larger shrimp falling through the larger grading apertures as the shrimp progress down said tray grading means;

said tray grading means including a series of adjacent, juxtaposed inclined trays, each comprising a series of elongated channels, each of said channels having an initial portion which is solid and an end portion which terminates in a grading slot of uniform width, said slot having a length being approximately equal to the length of the shrimp having a thickness substantially equal to said width, said slot serving as said size-grading aperture.

13. A shrimp grading machine for grading shrimp according to their size comprising:

- an upper frame portion;
- a basic frame support structure;
- mounting means for mounting said upper frame to said basic frame support structure;
- tray grading means mounting on said upper frame for grading and separating the shrimp according to size, said tray grading means including a series of size-grading apertures therein which progressively get larger as said tray grading means is progressed, said tray grading means including a series of inclined, elongated channel sections, each of said channel sections having an initial portion which is solid and an ending portion which terminates in a grading slot of uniform width, said slot having a length which is interdependent with the width of the slot, the length being approximately equal to the length of the shrimp having a thickness substantially equal to said width, said slots serving as said size-grading aperture; and

means for moving the shrimp down said channel sections; whereby shrimp move down said tray grading means and are separated and graded according to size by the smaller ones falling through the earlier encountered grading apertures and the larger shrimp falling through the larger grading apertures as the shrimp progress down said tray grading means.
